CLAIM

The ornamental design for an inflatable tube for aquatic activity, as shown and described.

DESCRIPTION

FIG. 1 is a front elevation view of an inflatable tube for aquatic activity showing the new design;
FIG. 2 is a back elevation view thereof;
FIG. 3 is a left-side view thereof;
FIG. 4 is a right-side view thereof;
FIG. 5 is a top plan view thereof;
FIG. 6 is a bottom plan view thereof;
FIG. 7 is a perspective view thereof; and,
FIG. 8 is another perspective view thereof.

The broken lines depicting a rope represent environmental structure that forms no part of the claimed design.
The additional broken lines in FIGS. 3, 4, 7 and 8 depict portions of the article that form no part of the claimed design.
